(57) **CLAIM**

The ornamental design for a wireless mouse, as shown and described.

DESCRIPTION

FIG. 1 is an upper rear left perspective view of a wireless mouse showing my new design;

FIG. 2 is a top plan view thereof;

FIG. 3 is a right side elevation view thereof, with the left side elevation view being a mirror image of the right side elevation view;

FIG. 4 is a bottom plan view thereof;

FIG. 5 is a front elevation view thereof; and,

FIG. 6 is a rear elevation view thereof.

The broken lines shown are included for the purpose of illustrating unclaimed portions of the Wireless Mouse and form no part of the claimed design.
